JET PUMP

Thomas H. Huff, Philadelphia, Pa.

Application November 23, 1935, Serial No. 51,315

2 Claims. (Cl. 230—95)

This invention relates to jet pumps, and more particularly to jet pumps actuating atmospheric air by means of compressed air as driving fluid. I have discovered through extensive tests that 5 such pumps can be considerably improved in performance by proportioning and shaping the same in a novel way, namely by positioning the jet discharge nozzle, and thereby the actuating jet, parallel but unsymmetrical to the surrounding pressure chamber or mixing portion of the fluid conduit, and further by tapering or flaring the discharge nozzle itself, at least at its exit side, but better at the entrance side also.

It is accordingly the broad object of the present invention to provide for a jet pump with an improved performance, as regards the economy, efficiency, magnitude of pressure or suction obtained, and range of different delivery volumes within which the performance is acceptable.

Another object of the invention is to provide 20 for such jet pump having a jet nozzle parallel with the surrounding portion of the conduit but out of alignment with its axis.

A still other object is to provide for such jet 25 pump having a flared discharge nozzle.

It is at last an object of this invention to provide for such jet pump having the parts, shape, and proportions described in the specification.

These and other desirable objects and advantages 30 of the present invention will be illustrated in the accompanying drawing and described in the specification, a certain preferred embodiment being disclosed by way of illustration only; for since the underlying principles may be incorporated in other specific devices, it is not intended to be limited to the one here shown except as such limitations are clearly imposed by the appended claims.

In the drawing like numerals refer to similar 40 parts throughout the several views, in which

Fig. 1 represents a longitudinal section through the jet pump,

Fig. 2 is a cross section on the line 2—2 of Figure 1, and

Fig. 3 is a longitudinal section through the jet nozzle of Figure 1, showing the same in an enlarged scale.

In Figure 1 there is shown an integrally cast 50 pump body 10 having a circular inlet 22 for the working fluid to be actuated, this fluid entering therein from the open or from a supply pipe not shown in the drawing, and connected to the pump body in any suitable manner. This fluid is then conducted through a straight, round, 55 cylindrical pressure chamber 11 where it passes

by the nozzle 18 to be described later. The actuated fluid passes next through the straight and round converging cone 12, the circular cross sections of which diminish gradually in size from that of the pressure chamber 11 to about one 5 fourth to one fifth thereof. The fluid is then received by the straight and round diverging cone 13 with circular cross sections gradually increasing in size from that of the exit cross section of the converging cone to a size substantially equal to that of the cross-section of the pressure chamber 11. It will be seen from Figure 1 that the divergent cone is much longer than the convergent cone, about three times as long, the two cones combining to form a Venturi tube, 15 the steepness of the conicity being in keeping with the scientific rules of streamlining, that is to say with more space devoted to the streamlining on the trailing side than to the streamlining on the leading side. The divergent cone 13 20 discharges the fluid into a discharge pipe not shown in the drawing and connected to said cone in any suitable manner, or the fluid is discharged into the open, as the particular purpose may require. It is also seen from Figure 1 that the 25 conduit composed of the pressure chamber 11 and of the two cones 12 and 13 possesses an axis of symmetry 14, which in this case is the axis of revolution common to the conduit portions 11, 12 and 13, their walls being generated by rotation 30 thereabout.

The actuating or driving fluid enters the pump at the threaded inlet 15 from a supply pipe not shown in the drawing. It passes through a valve 16 of any suitable construction, next through the hollow bracket 17 projecting from the wall of the pressure chamber into the same, and finally through the jet nozzle 18, from which it is discharged into the pressure chamber. This nozzle comprises an insert 23 screwed into bracket 17, 40 having a straight round flared entrance conduit 19 convergent in the direction of flow and a straight round conical exit portion 20 gently divergent in the direction of flow, so that the diameter of the cross section common to portions 19 45 and 20 is smaller than both the entrance diameter of portion 19 and the exit diameter of portion 20.

The nozzle portions 19 and 20 are coaxial, and 50 their common axis of symmetry 21, or axis of revolution, is parallel to the axis of symmetry 14 of the pressure chamber. According to the invention, however, the two axes 14 and 21 do not coincide, but they are deliberately spaced apart from each other, so that the nozzle 19 and 20, and 55

the pressure chamber 11 and 12, are parallel but not concentric. I have found that a distance between these two axes equal to about one twelfth of the pressure chamber diameter, or slightly 5 more, leads to a pronounced improvement in the performance of the pump, which eccentricity is larger than any small accidental eccentricity unavoidable with ordinary manufacturing methods. I have also found that one definite and fixed eccentricity takes care of a large range of operating 10 conditions, and that it is not necessary to make the eccentricity adjustable, for increasing the range of good performance, at least not ordinarily. I have therefore illustrated my invention 15 by showing a fixed eccentricity, which is the embodiment I prefer.

The beneficial effect of this eccentricity, manifested by experiment and trial, can probably be explained as follows: For an efficient pump performance it is necessary that the actuating fluid 20 mix with the working fluid and flow then through the venturi in positive contact with the walls thereof, not separated therefrom by fluid substantially at rest. A concentric jet has the tendency 25 to flow in the latter inefficient way, but a separated eccentric jet is unstable and cannot maintain itself, but rather makes contact with the walls on the side nearest to it and changes then to a contacting jet.

30 The beneficial effect of the flaring of the jet nozzle is believed to have special relation to the elasticity of the actuating fluid, compressed air. It is known in the turbine art that a flared exit 35 nozzle is conducive to large exit velocities of elastic fluids, such as steam. I would thus have discovered that the efficiency of jet pumps is increased by giving to the actuating jet a particularly high initial velocity before it mixes with the working fluid, the flared nozzle being a particular structure for bringing that about, and therefore of great use in connection with jet 40 pumps.

I have found that the other proportions shown

in the drawing are also important and should be substantially adhered to for the preservation of the efficiency and performance of the pump. The distance of the nozzle exit from the entrance cross section of cone 12, and the steepness of 5 the two cones 12 and 13 are of importance and should not be departed from without assurance that such departure is not harmful. With the pump as shown, using air compressed to about 100 pounds per square inch as actuating fluid, 10 and atmospheric air as working fluid, I have obtained a very strong air flow, and a suction up to 55 inches of water.

I claim:

1. A jet pump having a substantially cylindrical casing providing a rotund conduit for receiving and discharging the pumped fluid: said conduit comprising a substantially cylindrical portion, a first conical portion in conterminous relation to the cylindrical portion convergent in the 20 direction of flow, and a second conical portion in conterminous relation to said first conical portion divergent in the direction of flow; jet nozzle means in said cylindrical conduit portion positioned in spaced relation to and upstream of the entrance end of said first conical conduit portion parallel to but out of alignment with the conduit axis; and means for supplying driving fluid to the jet nozzle means.

2. In combination with a pressure supply line, 30 a casing comprising a substantially cylindrical conduit for receiving and discharging fluid constricted by a pair of conical conduit portions converging towards each other and coaxial with the conduit, and a single nozzle connected to 35 and receiving the entire flow from the pressure supply line, said nozzle having its discharge tip disposed eccentrically of the conduit axis but parallel thereto and positioned in spaced and upstream relation to the receiving end of the 40 constricted portion of the conduit.
